DESIGN FOR A DRESS

Aline Henry, New York, N. Y.

Application July 31, 1941, Serial No. 102,585

Term of patent 3½ years

To all whom it may concern:

Be it known that I, Aline Henry, a citizen of the United States, residing in New York city, in the county of New York and State of New York, have invented a new, original, and ornamental Design for a Dress, of which the following is a specification, reference being had to the accompanying drawing, forming part thereof.

Fig. 1 is a front view of a dress showing my new design, and

Fig. 2 is the rear view thereof on a reduced scale.

My design comprises a one-piece party dress having a fitted velvet bodice with puffed sleeves and a flared peplum which is split in front in association with a full skirt, which contrasts in fabric and color, as shown.

I claim:

The ornamental design for a dress, substantially as shown and described.

ALINE HENRY.
